UNITED STATES PATENT OFFICE

SEAVERN S. HILTON, OF WELD, MAINE, ASSIGNOR TO INTERWOVEN STOCKING COMPANY, OF NEW BRUNSWICK, NEW JERSEY, A CORPORATION OF NEW JERSEY

DESIGN FOR A DISPLAY STAND

Application filed June 28, 1932. Serial No. 44,211. Term of patent 14 years.

To all whom it may concern:

Be it known that I, SEAVERN S. HILTON, a citizen of the United States, residing at Weld, in the county of Franklin and State of Maine, have invented a new, original, and ornamental Design for Display Stands, of which the following is a specification, reference being had to the accompanying drawing, forming part thereof.

Fig. 1 is a side elevation of a display stand showing my new design.

Fig. 2 is a front elevation of the same.

I claim:

The ornamental design for a display stand, as shown.

Signed at Weld, in the county of Franklin, and State of Maine, this 22d day of June, 1932.

SEAVERN S. HILTON.
